UNITED STATES PATENT OFFICE.

FELIX J. COUGHLIN, OF VERSAILLES, OHIO.

PACKING CASE FOR PARACHUTES.

Application filed August 14, 1919. Serial No. 317,610.

To all whom it may concern:

Be it known that I, FELIX J. COUGHLIN, a citizen of the United States, residing at Versailles, in the county of Darke and State of Ohio, have invented certain new and useful Improvements in Packing Cases for Parachutes, of which the following is a specification.

The packing case opens instantly and releases the parachute in a position and situation to open freely. The situation and position of the packing case on the machine, in conjunction with its shape, makes it offer very slight resistance to the air as the machine travels. The case falls into position to discharge the parachute directly downward, so soon as the weight of the aeronaut is placed on the sling. The packing case's entire bottom opens out and the open area is so large that the parachute falls directly into the air, substantially without coming into contact with any part of the case, and substantially undisturbed from the condition in which it was packed.

Fig. 1 is a front elevation of the case closed and secured to the machine. Fig. 2 is a side elevation of the closed packing case. Fig. 3 is a view of the case when the parachute is just emerging. Fig. 4 is a view of the face of the packing case with the cover removed. Fig. 5 is a side elevation of a portion of the skirt. Fig. 6 is a section of a portion of the cover. Fig. 7 is an inside view of the top of the packing case. Fig. 8 is an inside view of the cover. Fig. 9 is a section on line 9—9 of Figs. 1 and 2. Fig. 10 is a rear view of the packing case and the suspension cords, as the latter will show when the device is attached to the machine.

The case is round and flat. One side is curved out so as to offer the least resistance possible to the air as the machine passes through it. The case is attached permanently to the part of the machine where it is carried by the cords, 20, and eye, 24. It is also attached so that it will permit it to break away at once, when a weight is put upon the sling, 3, of the parachute, by the cords, 7, 6. When the packing case is attached to the support, 1, (which may be the fuselage of an aeroplane or the basket of a balloon) in the position it will occupy when the machine it is attached to is in normal flight, it will be fastened to the support, by the cords, 20, which will be inactive. Their

position is shown in Fig. 10. It will also be held against it by the cords, 6, 7, which will hold it in place, as shown in Fig. 1. When the aviator has confined himself to the parachute, the connections, 2, between the cords, 6, 7, are broken, and they will cease to hold the case, which will then fall into the position shown in Fig. 3, the back, 21, upwards and hanging from the cords, 20.

The packing case has a back, 21, secured upon the hoop, 28. A skirt, 13, forms a retainer for the folded parachute, and is folded over it in folds, one of the folds being marked with the figure 14, and the cover, 5, which has the hole, 9, to allow the projection through it of the sling, 3, of the parachute, fits over the hoop, 28, enclosing the face of the case. The cover, 5, has preferably an elastic binder, 19, that is slipped over and holds it upon the hoop, 28, and so keeps the cover, 5, in place. Preferably in practice, it has the reinforce, 23.

The cords, 20, are spliced to the hoop, 28. The cover, 5, skirt, 13, and back, 21, are all made in practice of a water-proof textile material. The reinforce, 22, preferably forms part of the back of the case and holds the hanger, 26, to which the top of the parachute is fastened, by the customary frangible connections.

The skirt, 13, has the closing cord, 17, which in practice is arranged as follows:—A series of flaps, 15, are attached to the skirt, 13, and fitted with retainers, 16, for the cord, 17, which is laced from one to the other. In practice this cord, 17, is light enough to be broken very readily. It is best made weak enough to break in a number of places simultaneously, or otherwise fixed so that the break will free instantly the skirt, 13, and allow it to open at once and free the parachute packed beneath it. 18 shows where this cord can be knotted.

The attachment cords, 7, 6, are secured to the support, 1, in a suitable manner. In practice, loops are secured at their ends by the holders, 8, 8, and the slack is folded over the face of the packing case and is connected together by the frangible connection, 2, which in practice preferably passes through the sling, 3. The cords, 20, are preferably in practice bound together into an eye, 24, which is firmly secured to the support, 1.

Putting weight upon the sling, 3, breaks the frangible connections, 2 and 17. The

2
skirt, 13, flies open and releases the contained parachute. While these breaks are occurring the case falls into the position shown in Fig. 3 and hangs back upward 5 from the cords, 20. The parachute falls out from the opened face of the case, and breaks the connection with the hanger, 26, and is free. It is shown in Fig. 3 with the cover, 5, following the sling downwards and the 10 suspension cords, 11, just beginning to appear below the skirt, 13.

I claim—

1. The combination, in a packing case for parachutes, of a back, a hoop to which said back is attached, a skirt attached to the hoop, 15 and adapted to fold over inward, on the face of the case, and a cover having an aperture

therein, and removably fastened to the back of the case.

2. The combination, in a packing case for 20 parachutes, of a back, a hoop to which the back is secured, a skirt adapted to fold over on the face of the case and held in folded position by parachute connections, and a removable cover. 25

3. The combination, in a packing case for parachutes, of a back, a hoop to which the back is secured, a skirt adapted to fold over on the face of the case and a cover having a central hole and an elastic binding adapted 30 to clasp the hoop.

In testimony whereof I affix my signature.

FELIX J. COUGHLIN.
